GATE CONTROL FOR FILLING COLUMNS

Forrest C. Simon, Piqua, Ohio, assignor to The French Oil Mill Machinery Company, Piqua, Ohio

Application July 18, 1950, Serial No. 174,422

11 Claims. (Cl. 193—32)

1 This invention relates to gate controls for filling columns, by which measured charges of materials may be passed in succession along a filling passage. Gates of this type are used extensively in filling columns for solvent extractor devices. Filling columns commonly have top and bottom gates separately operable by mechanical or hydraulic means. When the bottom gates are opened, the opening movement has been rapid and the material discharged or released by that gate drops suddenly and rapidly into an extraction basket. The sudden dropping of the material causes some of it to spill over the basket sides and the baskets do not fill evenly.

An object of this invention is to provide an improved control for gates for filling columns which will eliminate substantial spilling of the materials controlled as they are delivered to the baskets, which will cause even filling of the baskets, which will not objectionally delay delivery of the materials to the baskets, which will not greatly increase the cost of the control which will cause movement of the gate in a manner to deliver a charge of materials to a basket as a stream in contrast to dropping the materials suddenly in one mass, and which will be relatively simple, practical and inexpensive.

Other objects and advantages will be apparent from the following description of some embodiments of the invention, and the novel features will be particularly pointed out hereinafter in connection with the appended claims.

In the accompanying drawings:

Fig. 1 is a side elevation of the filling column for a solvent extractor, having gates for controlling flow of materials to be extracted therealong, one of the gates being controlled in accordance with this invention;

Fig. 2 is a side elevation of a portion of the same to show the hesitation valve and its connection to the gate;

Fig. 3 is an enlarged, vertical section of the hesitation valve;

Fig. 4 is a schematic diagram of the controls for the bottom gate;

Fig. 5 is a sectional plan of the cam shaft and valves, which form a part of the controls; and

Fig. 6 is an end elevation of the cam shaft and valve shown in Fig. 5.

In the illustrated embodiment of the invention, and referring first particularly to Fig. 1, the apparatus includes an upright filling column 1 which has a passage therethrough from end to end, the upper end being connected to a bin or other supply of loose solids that are to be extracted; and

2 the bin not shown because it forms no part of the present invention. This column 1 is formed of sheet metal or other suitable material, and is provided adjacent, but slightly below its top, with a pair of horizontal shafts 2 and 3 which are rockably mounted on axes in a horizontal plane. Each shaft within the column carries a plate 4 extending therefrom so that by rocking the shafts 2 and 3, the plates 4 may be moved until they meet at their free ends, as shown in Fig. 1. By rocking the shafts 2 and 3 in the opposite direction, the plates 4 may be separated into the position shown by the dot and dash lines 4a. The plates 4 and the shafts 2 and 3 form what may be referred to as the top gate in this filling column. An arm 5 is fixed upon the shaft 2 to extend radially therefrom, and a similar arm 6 is fixed to shaft 3 to extend radially therefrom. The free ends of the arms 5 and 6 are pivotally connected by pins 7 to a connecting link 8, and the arms 5 and 6 are in the relative positions shown in Fig. 1 when the plates 4 are in contact to close the gate.

Also fixed on the shaft 2 is another arm 9 which carries a counterweight 10 at its free end, and at an intermediate point it is pivotally connected by a pin 11 to a yoke 12 which straddles the arm 9, with the pin 11 passing through the arms of the yoke 12 and the arm 9. The yoke 12, at its base or a cross part, is adjustably connected, such as by threading, to a piston rod 13 which extends through a stuffing box 14 into a cylinder 15 that is closed at both ends. The cylinder 15 is hollow, and within it the inner end of the piston rod 13 is provided with a piston 16 which is somewhat like a cylinder of a steam or gasoline engine. The piston is preferably provided with piston rings to provide a sliding seal between its periphery and the cylinder wall. Pipes 17 and 18 lead to opposite ends of the cylinder 15 for supplying operating fluid thereto or releasing it therefrom.

The cylinder 15 is received between the arms of a yoke 19, and the cylinder has trunnions 20 at diametrically opposite sides of its midlength which are rockably mounted in the arms of the yoke 19. The yoke 19, at its base or cross part, is anchored to the column 1. By admitting operating fluid to opposite ends of the cylinder 15, the piston 16 may be caused to reciprocate and cause the plates 4 to rock between open and closed positions.

Below the top gate in the filling column, and spaced therefrom, is a bottom gate which is formed of plates 21 similar to the plates 4. One

of these plates 21 is attached to a shaft 22 which is rockably mounted in the housing in a horizontal position at one side of the passage through column 1. The other plate 21 is attached to a shaft 23 similarly rockably mounted at the opposite side of the passage through the column 1. The plates 21 are downwardly inclined with their free ends substantially abutting, as shown in Fig. 1, when the bottom gate is closed, and when the shafts 22 and 23 are rocked in the proper direction, the plates 21 swing downwardly into the dot and dash positions 21a, which represent the open position of the bottom gate. An arm 24 is fixed upon the shaft 22 and extends radially therefrom and generally toward the shaft 23. A similar arm 25 is fixed upon the shaft 23 and extends radially therefrom. The free ends of the arms 24 and 25 are pivotally connected by pins 26 to the ends of a connecting link 27 which serves to connect the arms 24 and 25 in the angular relationship shown in Fig. 1, when the plates 21 are meeting at their free ends.

Another arm 28 is fixed upon the shaft 23 to rock therewith, and the free end of this arm 28 carries a counterweight 29 which is adjustable into different positions along the end of the arm in order to vary its turning torque on the shaft 23. A yoke 30 straddles the arm 28 between the weight 29 and the shaft 23, and a pivot pin 31 extends through the arms of the yoke 30 and the arm 28 so as to pivotally connect the yoke to the arm. The yoke, at its base or cross part, is threaded to one end of a piston rod 32. The rod 32 extends upwardly from the yoke and through a stuffing gland 33 into the chamber of cylinder 34, which is closed at both ends. Within the cylinder 34, the piston rod 32 carries a piston or piston head 35 which resembles the piston 16, and it also carries a plurality of piston rings on its periphery which engage the inner wall of the cylinder 34 and provide a sliding seal between the piston and the cylinder wall. Pipes 36 and 37 are connected to the opposite ends of the cylinder 34 so as to supply operating fluid to the chamber of the cylinder 34 at opposite sides of the piston 35.

The cylinder 34 is disposed between the arms of a yoke 38, the trunnions 39 on diametrically opposite sides of the cylinder 34 pass through the arms of a yoke 38 and are rockably mounted therein so that while the piston 34 is held in the yoke 38, it is free to rock about the axis of the trunnion 39. The yoke 38, at its base or cross part, is also attached to the filling column 1. The piston 35 and cylinder 34 thus serve to rock the shafts 22 and 23 in directions to close the gate or open it. The column 1 at its bottom is convergingly tapered at 40 so as to direct loose solids released by the gate, as a stream, that may be delivered to the baskets of an extractor or for any other purpose.

Secured on the side of the column 1, between the top and bottom gates, is a hesitation valve 41, having a passage 42 therethrough from end to end. A valve rod 43 extends through the valve 41 and from both ends thereof, and the ends of the valve casing through which the rod 43 passes may be suitably packed to retard leakage along the rod 43. The rod 43 reciprocates endwise in the passage 42, and in the portion always within the passage 42 the rod 43 is reduced in diameter, as at 44. The housing of the valve 41 is provided with ports 45 and 46 which are spaced apart along the length of the passage 42 by a distance not greater than the length of 70

the reduced portion 44, so that the rod 43 may, in one position, place the reduced portion 44 in a position to connect the ports 45 and 46, as shown in Fig. 1.

When the rod 43 moves downwardly from that position, the reduced portion 44 will move out of alignment with the port 45 and close the passage between the ports 45 and 46, and this disconnection of ports 45 and 46 will continue as the valve rod 43 continues to move downwardly. The lower end of the rod 43 is threaded at 47 into a coupling 48, and secured in adjusted position in the coupling 48 by a lock nut 49 which is threaded on the end 47 to engage against the end of the coupling 48. The lower end of the coupling 48 is pivotally connected to the upper end of a link 50, see Fig. 2, by a pivotal coupling pin 51. The lower end of the link 50 is forked and straddles the arm 25 on the shaft 23 between its ends, and is pivotally connected thereto by a pin 52. Thus, as the arm 25 rocks downwardly from the position shown in Fig. 1, it will pull the rod 43 downwardly in the valve 41. The pivotal couplings 51 and 52 allow the pin 52 to follow the arcuate path of travel with the arm 25 while the valve rod 43 reciprocates endwise.

Referring next to Fig. 4, the port 45 is connected by a pipe 36 to the lower end of the cylinder 34, and the port 46 of valve 41 is connected by a pipe 53 to one port of a control valve 54, similar in construction to the well known 4-way reversing valve used to control double-acting hydraulic rams. Another port of the valve 54 is connected by the pipe 37 to the upper end of the cylinder 34. The pipes 17 and 18 that are connected to opposite ends of the cylinder 15 are connected to different ports of a control valve 55 similar to valve 54. Another valve 56 also similar to valve 54 has one port connected by a pipe 57 to the pipe 36 between the hesitation valve 41 and the cylinder 34, and has another port thereof connected by a pipe 58 to the pipe 37. Each of the valves 54, 55 and 56 has a central port connected to a pipe 59, and these pipes 59 are connected together and to a source of operating fluid under pressure (not shown). These valves 54, 55 and 56 may be common three-way valves, and each has a reciprocating valve element 60 which is shiftable endwise within the valve housing but extends outwardly for operation.

When the valve element 60 is moved endwise in one direction, it connects its pipe 59 to one of the ports of that valve and vents the other port, and when moved in the opposite direction, it vents the first mentioned port and connects the pipe 59 to the other port which had previously been vented. Thus, the valve serves to direct operating fluid under pressure alternately to opposite ends of one of the operating cylinders. For example, the valve 54 serves to deliver operating fluid under pressure alternately to opposite ends of the cylinder 34, so as to move the piston 35 endwise and open or close the bottom gate. The valve 55 serves to deliver operating fluid under pressure alternately to opposite ends of the cylinder 15 so as to move the piston 16 endwise and open or close the top gate, depending upon the direction of the movement of the piston 16.

It will be noted that the valve 56 also delivers operating fluid under pressure alternately to opposite ends of the cylinder 34 independently of the hesitating valve. The hesitating valve controls the movement of operating fluid from valve

54 to the lower end of cylinder 34. Each of the operating elements 60 of the valves 54, 55 and 56 carries a roller 61 on its free end which rides against a cam by which it may be operated endwise in one direction. Each valve 54, 55 and 56 is spring operated in a direction to move the valve element 60 outwardly of the housing.

Mounted in a suitable auxiliary frame 62, Figs. 5 and 6, is a cam shaft 63 which is rotated by means of a sprocket wheel 63a on one end thereof. Arranged along the shaft 63 are a plurality of adjustable cams 64, 65 and 66 which may be adjusted angularly on the shaft independently of each other, and each secured in an adjusted, angular position on the shaft for rotation therewith. The rollers 61 engage against their respective cams 64, 65 and 66, so that the valves 54, 55 and 56 are operated in a desired sequence with proper time intervals between operations. Also mounted in the frame 62 are other valves and cams for operating the same. Since they form no part of the present invention, they will not be described. They serve to control other operations of a related solvent extractor mechanism.

The operation of the apparatus will now be described. Heretofore, when the bottom gates are opened by mechanism or by hydraulic means, they open rapidly and the material released thereby drops suddenly as a mass down the filling column into a basket beneath the tapered bottom 40, and as a result, some of the material tends to spill over the basket sides of the solvent extractor apparatus, and also the baskets do not usually fill evenly. In order to obtain the most efficient extraction, the baskets should be evenly filled. The use of the hesitating valve serves to prevent this spilling over the basket sides and the uneven filling of the baskets. The solid particles to be extracted are delivered to the upper end of column 1 where they are stopped by the top gate formed by the plates 4.

The cam shaft 63 is operating continuously, and in due time the cam 66 operates the valve 55 that in turn causes an operation of the cylinder 15 to open the top gate and allow the material to pass down the column until it is stopped by the bottom gate, which is closed at that time. After a short interval, determined by the setting of the cam 66, the valve 55 is operated to close the top gate and hold it closed for the balance of the cycle of operation. After the top gate is closed, the cam 64 operates the valve 54 to admit operating fluid under pressure from a pipe 59 to the pipe 53, and vents the pipe 37. This fluid passes through pipe 53 and through the hesitation valve 41 to the pipe 36, thence to the lower end of the cylinder 34. It will be understood that the valve rod 43 is in its upper position shown in Figs. 1 and 3 at this time, because the bottom gate is closed. The piston 35 moves upwardly and moves the bottom gate towards open position.

As the bottom gate starts to open, the valve rod 43 moves downwardly with the gate, and after a predetermined extent of movement, which may be varied to some extent by the threading of the rod 47 into the coupling 48, the reduced part 44 of the valve rod 43 will move out of alignment with port 45 and thus break the connection between the pipe 53 and pipe 36. This will stop further upward travel of the piston 35 and thus stop the opening movement of the bottom gate in a position where the gate is open only to the desired slight extent. The bot-

tom gate will remain in this position so long as the hesitation valve is in this condition, except in a manner which will be described presently. When the bottom gate is partially open, such as to have an opening two to three inches wide between the free ends of the gate plates, the material may pass through as a stream and will not drop out of the gate in one mass. It percolates slowly through the narrow opening so that it will not spill over the edges of the baskets, and the baskets will be filled with the loose solids more evenly.

The cam shaft and the setting of the cams thereon will, after a predetermined interval of time, such as about 5-10 seconds, or a time sufficient to pass a large percentage of the material going through the small gate opening, then cause the cam 65 to operate the valve 56 so as to deliver operating fluid under pressure from pipe 59 through the pipe 57 to the pipe 36 and thus bypass the hesitation valve 41. Operating fluid may now flow to the lower end of the cylinder 34 and cause the piston 35 to again move upwardly until the bottom gate is fully opened. The pipe 58 permits the upper end of the cylinder 34 to be vented because it vents the pipe 37 even though the valve 54 may have been operated by its cam to close the connection to the pipe 53 before the piston 35 completes its upper stroke.

After a further interval of time, the cam 65 closes the valve 56 and reverses the operation of the piston 35 to again close the bottom gate so that the bottom gate will be closed before the cycle is completed and the top gate again opens. The bottom gate may remain fully open for approximately two seconds and then a cam operates the valve to close the bottom gate. It will thus be observed that the bottom gate is stopped in a partially open position momentarily during its opening movement and then its movement is continued, all controlled automatically.

It will be understood that various changes in the details and arrangements of parts, which have been herein described and illustrated in order to explain the nature of the invention, may be made by those skilled in the art within the principle and scope of the invention as expressed in the appended claims.

I claim:

1. A filling device comprising an upright filling conduit, a plurality of gates in said conduit and spaced apart vertically to stop the flow of material along the conduit at different positions but operable individually between open and closed positions, a fluid operated motor connected to and operating the upper of said gates between open and closed positions, another fluid operated motor connected to and operating the lower of said gates between open and closed positions, a valve for each motor, pipes from each valve to its motor to control operation of the motor and open or close the gate, a hesitating valve in series in the pipe to that side of the motor for the lower gate which controls the operation of the motor in a direction to cause opening of the lower gate, an operating connection from said hesitating valve to the lower gate for moving said hesitating valve from open position to closed position, when the lower gate is partly but not fully open but operable further in the same direction as the lower gate moves to fully open position, an auxiliary valve, a pipe connecting said auxiliary valve to said that side of the motor for the lower gate, and separate

from said hesitating valve, and a connection for supplying operating fluid under pressure to each valve, whereby when said lower gate is caused to open by operation of its related control valve, it will partly open and stop until said auxiliary valve is operated to bypass said hesitating valve and cause continued opening of said lower gate to fully open position.

2. A filling device comprising a generally upright filling conduit, upper and lower gates spaced apart along said conduit and individually operable between open and closed positions to control flow of materials along said conduit, an individual, fluid operated motor for each gate to operate it between open and closed position, a valve controlled, hydraulic circuit for each motor, a hesitating valve in series in the motor circuit that causes an opening of said lower gate and connected for operation by said lower gate from open position when the lower gate is closed, to closed position when the lower gate is partly closed, and movable further as the lower gate moves to fully open position, an auxiliary circuit for bypassing fluid around said hesitating valve, and an auxiliary valve controlling said auxiliary circuit.

3. A filling device comprising a generally upright filling conduit, upper and lower gates spaced apart along said conduit and individually operable between open and closed positions to control flow of materials along said conduit, an individual, fluid operated motor for each gate to operate it between open and closed position, a valve controlled, hydraulic circuit for each motor, a hesitating valve in series in the motor circuit that causes an opening of said lower gate and connected for operation by said lower gate from open position when the lower gate is closed, through closed position when the lower gate is partially closed, and to a further position when the lower gate is moved to fully open position, an auxiliary circuit for bypassing fluid around said hesitating valve, an auxiliary valve controlling said auxiliary circuit, a cam shaft mounted for rotation, and a plurality of cams on and rotating with said shaft and operating said valves in a desired sequence.

4. A filling device comprising a generally upright filling conduit, a gate movable between a closed position, a partially, but not fully open position, and a fully open position, to control the flow of materials along said conduit, a fluid operated motor connected to said gate to cause its operation in opposite direction, a fluid circuit including said motor to operate it, a controlling valve in said circuit, a hesitating valve in series in said circuit and having three positions in one of which it is open and in the others it is closed, said hesitating valve being connected to said gate for operation thereby, from open position when the gate is closed to closed position when the gate is partly, but not fully open, and when fully open, whereby when said gate is closed, operating fluid to open the gate may pass through said hesitating valve to said motor, and when the gate is partly open the hesitating valve is closed to stop the opening movement of the gate, and a valve controlled auxiliary circuit for bypassing said hesitating valve when said valve is in closed position to cause continued opening movement of said gate.

5. A filling device comprising a generally upright filling conduit, a gate movable between a closed position, a partially, but not fully open position, and a fully open position, to control

the flow of materials along said conduit, a fluid operated motor connected to said gate to cause its operation in opposite direction, a fluid circuit including said motor to operate it, a controlling valve in said circuit, a hesitating valve in series in said circuit and having three positions in one of which it is open and in the others it is closed, said hesitating valve being connected to said gate for operation thereby, from open position when the gate is closed to closed position when the gate is partly, but not fully open, and when fully open, whereby when said gate is closed, operating fluid to open the gate may pass through said hesitating valve to said motor, and when the gate is partly open the hesitating valve is closed to stop the opening movement of the gate, a valve controlled auxiliary circuit for bypassing said hesitating valve when said valve is in closed position to cause continued opening movement of said gate, and means for operating said valves in a desired sequence.

6. A filling device comprising a generally upright filling conduit, a gate movable between a closed position, a partially, but not fully open position, and a fully open position to control the flow of materials along said conduit, a fluid operated motor connected to said gate to cause its operation in opposite direction, a fluid circuit including said motor to operate it, a controlling valve in said circuit, a hesitating valve in series in said circuit, and having three positions in one of which it is open and in the others it is closed, said hesitating valve being connected to said gate for operation thereby, from open position when the gate is closed to closed position when the gate is partly, but not fully open, and when fully open, whereby when said gate is closed, operating fluid to open the gate may pass through said hesitating valve to said motor, and when the gate is partly open the hesitating valve is closed to stop the opening movement of the gate, a rotatable cam shaft, a plurality of cams on and rotating with said shaft, one of said cams operating said controlling valve, an auxiliary valve operated by another of said cams, and an auxiliary circuit from said auxiliary valve to said motor and bypassing said hesitating valve, whereby after said gate has been partially opened by said motor and stopped by operation of said hesitating valve, the subsequent operation of said auxiliary valve may cause further operation of said motor to fully open the gate.

7. A filling device comprising a generally upright filling conduit, a gate movable between closed, partially open and fully open positions to control the flow of materials along said conduit, a power actuated motor connected to said gate to cause its operation in opposite directions between said positions, power circuits connected to said motor to deliver operating power thereto and cause its operation in opposite directions selectively, a selectively operable controller for delivering power alternately to said circuits to cause the operation of said motor, a hesitating control element in series in that power circuit which is active while the motor is being operated toward open position, connected to said gate for operation thereby, and operable by said gate from an open position when the lower gate is closed, into a position in which it stops delivery of power to said motor when the gate is partially but not fully open, and into a further position when the lower gate moves into fully open position, a bypass circuit connected to said motor to deliver power to said motor in place of that interrupted

by said hesitating element to cause resumption of operation of said motor, and further movement of said gate into fully open position, and a selectively operable controller for said bypass circuit.

8. A filling device comprising a generally upright filling conduit, a gate movable between closed, partially open and fully open positions to control the flow of materials along said conduit, a power actuated motor connected to said gate to cause its operation in opposite directions between said positions, power circuits connected to said motor to deliver operating power thereto and cause its operation in opposite directions selectively, a selectively operable controller for delivering power alternately to said circuits to cause the operation of said motor, a hesitating control element in series in that power circuit which is active while the motor is being operated toward open position, connected to said gate for operation thereby as the gate moves from closed to fully open position, and operable by said gate into an intermediate position in which it stops delivery of power to said motor when the gate is partially, but not fully open, a bypass circuit connected to said motor to deliver power to said motor in place of that interrupted by said hesitating element to cause resumption of operation of said motor and further movement of said gate into fully open position, a selectively operable controller for said bypass circuit, and a cam shaft carrying cams for operating said controllers in a desired sequence.

9. A filling device comprising a descending conduit, a gate controlling flow of materials along said conduit, a fluid operated motor connected to said gate to operate it in opposite directions between open and closed positions, a hesitation valve connected for operation by said gate and motor between a closed position of the gate into a fully open position of the gate, and closed during an intermediate portion of its travel but open during an initial opening portion of the gate movement, a rotatable cam shaft, a plurality of control valves operated in a selected sequence from said shaft, a pipe connecting the first operated control valve to that side of said motor which causes an opening of the gate and having said hesitation valve in series therein, a pipe connecting another of said control valves to said motor at the same side thereof as said first pipe to bypass the hesitation valve, whereby said motor when operated will first open the gate until stopped by a closing of said hesitation, and then will continue its opening when said another control valve is operated by said cam shaft.

10. A filling device comprising a gate, a motor connected to and operating said gate between open and closed positions, power means con-

trolling said motor and selectively causing opening and closing movements of the gate, a delay device included in said power means to stop the opening movement of the gate by interruption of operation of said power means, and connected to the gate for operation thereby into gate stopping position when the gate reaches a selected intermediate position in its opening movement, and means for neutralizing the effect of said delay device a selected interval after movement of said gate is stopped in said intermediate position, to enable continued movement of said gate into fully open position.

11. A filling device having a descending conduit for delivering loose solids, which comprises a gate for controlling flow of said materials down said conduit, a fluid operated motor connected to and moving said gate in both directions between open and closed positions, a hesitation valve having a valve element connected to and moving with said gate and motor between closed and fully open positions of the gate, a rotatable cam shaft, a pair of control valves operated in sequence by said shaft during its operation, a source of operating fluid under pressure connected to each of said control valves, pipes leading from the first of said valves to be operated in a sequence, to the opposite sides of said motor to cause operation of said motor in opposite directions alternately upon successive operations of said first of said valves, said hesitation valve being connected in series in that one of said pipes from said first control valve that causes an opening of said gate and operable by the gate into closed position when the gate reaches an intermediate position in its opening movement, and a pipe connecting the second of said control valves to be operated in said sequence to that side of said motor which causes an opening movement of said gate.
